DESIGN FOR AN EMBLEM.

40,932.

Specification for Design.

Patented Oct. 11, 1910.

Application filed August 6, 1910. Serial No. 576,021. Term of patent 7 years.

To all whom it may concern:

Be it known that I, CHARLES L. THATCHER, a citizen of the United States, residing at Providence, in the county of Providence and State of Rhode Island, have invented a new, original, and ornamental Design for an Emblem, of which the following is a specification, reference being had to the accompanying drawing, forming part thereof.

The figure is a face view of my new design for an emblem.

The design consists of a valise on which is marked the letters U. C. T. and over the valise is formed a crescent, the whole being surrounded by a wreath.

I claim:

The ornamental design for an emblem, as shown and described.

CHARLES L. THATCHER.
